METHOD OF STABILIZING RAW GASOLINE

Brunner C. Barnes, Dallas, Tex., assignor, by
mesne assignments, to Socony-Vacuum Oil
Company, Incorporated, New York, N. Y., a
corporation of New York

Application July 1, 1950, Serial No. 171,620

4 Claims. (Cl. 196—11)

1

This invention relates to the recovery of liquid hydrocarbons from wet gas and relates more particularly to the stabilization of raw gasoline obtained from wet gas by the compression-refrigeration method.

Hydrocarbon gas containing butane, pentane, hexane and perhaps heavier hydrocarbons in addition to lighter hydrocarbons such as propane, ethane, or methane, may be treated in a variety of ways to separate and recover therefrom a heavy hydrocarbon fraction. One way of obtaining a heavy hydrocarbon fraction from a wet gas, called a wet gas because of the presence of heavy liquid hydrocarbons that may be obtained therefrom in the liquid phase, is by the compression-refrigeration method which involves compression and cooling of the gas whereby the heavy hydrocarbons enter the liquid phase and separation of the liquid hydrocarbons from the gaseous hydrocarbons is thereby effected. Depending upon the extent of the compression and the cooling and the composition of the wet gas, the composition of the liquid phase, or gasoline, will vary. Thus, gas obtained from a petroleum hydrocarbon reservoir, for example, may be treated by compression and cooling to obtain gasoline containing pentane and higher hydrocarbons, butane and higher hydrocarbons, or propane and higher hydrocarbons. Hereinafter, the liquid phase obtained by compression and cooling will be termed gasoline irrespective of its composition. The raw gasoline obtained by compression and cooling is "wild," i. e., contains some of the lighter hydrocarbons of the wet gas which are undesired in the finished product, and the raw gasoline must be treated, or stabilized, to remove the light hydrocarbons and provide the finished product. Heretofore, the raw gasoline has been stabilized by fractionation. However, fractionation involves condensation of the vaporous overhead to provide the necessary reflux, and requires the use of condensers, reflux accumulators, pumps, and reflux control equipment.

It is an object of this invention to provide a method for stabilizing the liquid hydrocarbon phase obtained from wet gas by the compression-refrigeration method. It is another object of this invention to reduce the cost of stabilizing raw gasoline obtained from wet gas by the compression-refrigeration method. It is another object of this invention to reduce the amount of equipment required for stabilizing raw gasoline obtained from wet gas by the compression-refrigeration method. Further objects of the invention will become apparent from the following detailed description thereof.

2

In accordance with the invention, a wet gas is treated by compression and refrigeration to obtain raw gasoline, the raw gasoline is heated in a heating zone to an extent sufficient to vaporize the undesired light hydrocarbons, the vaporized hydrocarbons are contacted with cold raw gasoline supplied from the compression-refrigeration steps, the raw gasoline after contacting with the vaporized hydrocarbons is passed to the heating zone, the vaporized hydrocarbons after contacting with the cold raw gasoline are recycled to the compression-refrigeration steps, and stabilized gasoline is recovered from the heating zone.

Referring now to the accompanying figure which is a schematic flowsheet illustrating one embodiment of the invention, wet gas enters the system through line 10. The gas may be wet natural gas from a subterranean petroleum hydrocarbon reservoir, wet gas obtained from a petroleum refining operation, such as cracking still gas, or any other type of gas containing hydrocarbons that may be separated therefrom in the liquid phase by compression and cooling. The flowsheet will be described in connection with the treatment of a wet natural gas to obtain a gasoline product containing propane and the heavier hydrocarbon components of the gas although it will be understood that the process is applicable to the treatment of a wet gas to obtain a gasoline product having any desired hydrocarbon as the lowest boiling component thereof. The gas entering through line 10 is compressed in low stage compressor 11 to a pressure which may be, for example, about 85 pounds per square inch gage and is then passed through line 12 to low stage cooler 13 wherein the temperature is reduced by indirect heat exchange with water to about 95° F., for example. As a result of the compression in compressor 11 and cooling in cooler 13, liquid hydrocarbons are condensed from the gas and the mixture of gas and liquid hydrocarbons is passed through line 14 to low stage accumulator 15. The liquid hydrocarbons are removed from the accumulator through line 20 and the gas is removed through line 21.

The gas in line 21 is passed to high stage compressor 22 where the pressure is increased to about 265 pounds per square inch gage, for example, and is then passed through line 23 to high stage cooler 24 where the temperature is reduced by indirect heat exchange with water to about 95° F., for example. Additional liquid hydrocarbons are condensed in the high stage compressing and cooling operations and these hydrocarbons along with the remaining gas are passed through line 25 to high stage accumulator 26.

3

The liquid hydrocarbons are removed from the accumulator through line 31 and the gas is removed through line 32.

The gas in line 32 still contains hydrocarbons, such as propane and butane, that may be condensed to the liquid phase by cooling to a lower temperature. However, the gas may also contain water vapor which, upon additional cooling of the gas, will freeze and condense or form hydrocarbon hydrates with resultant clogging of lines 10 and equipment. Accordingly, the gas is passed to dehydration contactor 33 wherein it is contacted with a suitable type of desiccant to remove the water vapor therefrom. The dried gas is then passed through line 34 to refrigeration chiller 35 where it is cooled to a temperature of about 0° F., for example, by indirect heat exchange with any suitable type of refrigerant commonly employed for the purpose. As a result of the refrigeration, practically all of the propane and any heavier hydrocarbons are converted to the liquid phase. The gas and the condensed hydrocarbons are then passed through line 48 to refrigeration accumulator 41 from which the liquid hydrocarbons are withdrawn through line 42. The residual gas is withdrawn through outlet line 43 for utilization as desired.

The liquid hydrocarbons in lines 31 and 42 are combined and passed through line 43 to condense flash tank 44 wherein the pressure is decreased to about 40 to 50 pounds per square inch gage, for example, whereby a portion of ethane and methane dissolved in the condensed hydrocarbons is released from solution. The ethane and methane are removed from the top of the 35 accumulator through line 45 and are passed to line 21 for admixture with the gas entering high stage compressor 22 whereby any propane or heavier hydrocarbons removed from solution along with the methane and ethane are recovered 40 in the liquid streams in lines 31 and 42. The liquid hydrocarbons leave the condensate flash tank through line 50.

The liquid hydrocarbons in lines 50 and 20 comprise the raw gasoline product. The raw gasoline in line 20 contains ethane and methane dissolved therein and the raw gasoline in line 50 also contains ethane and methane dissolved therein, the release of ethane and methane from solution in condensate flash tank 44 not being complete. The raw gasoline streams are combined and passed through line 51 to stabilizer 52. Stabilizer 52 comprises a stripping column 53 and a reboiler 54, the stripping column being provided with a pressure controller 55 on gas outlet line 56, and the reboiler being provided with a heater 57, which may be a steam coil, and a temperature controller 60 operating valve 61 on the inlet line to the heater. The stripping column may be a packed tower or a tray or bubble plate tower and should have a stripping efficiency of two or more theoretical plates.

The raw distillate gasoline passes downwardly through the stripping column and enters the reboiler wherein it is heated by means of the heater 57. The amount of heat provided by heater 57 is sufficient to maintain the temperature of the liquid hydrocarbons in the reboiler at a point such that, under the pressure at which the stabilizer is being operated, the ethane and methane will be vaporized from the liquid hydrocarbons and form a gaseous phase passing upwardly through the stripping column 53. For example, with the stabilizer operating at 26 pounds per square inch gage the temperature is maintained

4

at about 75° F. Temperature controller 60 is connected by lead line 62 to the reboiler and serves to maintain the desired temperature, by opening and closing valve 61 to which it is connected by lead line 63, in accordance with well known principles. The gas phase containing the ethane and methane vaporizing from the liquid hydrocarbons will carry with it a portion of vaporized propane and higher hydrocarbons. The gas phase passing upwardly through the stripping column 53 countercurrently contacts the downwardly flowing stream of cold raw gasoline entering the column through line 51, whereby the countercurrently flowing cold raw gasoline acts as reflux and selectively resorbs the propane and heavier hydrocarbons from the upwardly flowing gas phase.

The ethane and methane are removed substantially entirely from the gasoline by the heating in reboiler 54. However, the propane and heavier hydrocarbons are not entirely removed from the gases flowing upwardly through the stripping column by the downwardly flowing stream of cold raw distillate gasoline, and, further, the upwardly flowing gases vaporize some of the propane and heavier hydrocarbons from the raw distillate gasoline. Accordingly, the upwardly flowing gases, after contacting with the downwardly flowing cold raw distillate gasoline, are removed from the column through line 56 and admixed with the 30 inlet gas in line 16 whereby the propane and heavier hydrocarbons are recovered by passage through the compression-refrigeration system. The stabilized gasoline is removed from the stabilizer through line 64.

Various modifications in the above described procedure may be made by those skilled in the art. For example, the compression and cooling of the gas may be conducted in a greater or lesser number of stages. Further, the extent of the compression and cooling may be varied to obtain raw gasoline as liquid product having different compositions with respect to the light constituents thereof. Also, by varying the temperature and pressure of the liquid in the reboiler 54, the composition of the stabilized gasoline can be varied. Other modifications will suggest themselves to those skilled in the art.

Having thus described my invention, it will be understood that such description has been given by way of illustration and example and not by 50 way of limitation, reference for the latter purpose being had to the appended claims.

I claim:

1. A process for the separation and recovery of a stabilized liquid fraction from a wet hydrocarbon gas mixture comprising passing a feed stream of said gas to a first compression zone and to a first cooling zone, compressing and cooling said gas in said compression zone and said 55 cooling zone to a pressure and temperature to condense from said gas a cold liquid hydrocarbon fraction, passing said gas and said cold liquid fraction to a first separation zone, separating uncondensed gas from said cold liquid fraction in said first separation zone, removing cold liquid fraction from said first separation zone, passing directly to a gas-liquid contact zone said cold liquid fraction at a temperature not substantially higher than its temperature in said first separation zone, removing uncondensed gas from said 60 first separation zone, passing said gas from said first separation zone to a second compression zone and to a second cooling zone, compressing and cooling said gas in said second compression zone and said second cooling zone to a pressure

and temperature to condense from said gas a cold liquid hydrocarbon fraction, passing said gas and said cold liquid fraction to a second separation zone, separating uncondensed gas from said liquid fraction in said second separation zone, removing uncondensed gas from said second separation zone, removing said cold liquid fraction from said second separation zone, passing said cold liquid fraction from said second separation zone to a pressure reduction zone, reducing the pressure on said cold liquid fraction in said pressure reduction zone to separate a gas phase therefrom, removing said gas phase from said pressure reduction zone, admixing said gas phase removed from said pressure reduction zone with said gas entering said second compression and cooling zones, removing said liquid fraction from said pressure reduction zone, passing said liquid fraction to said gas-liquid contact zone, passing said liquid fractions through said gas-liquid contact zone to a heating zone, heating said liquid fractions in said heating zone to stabilize said liquid fractions by vaporizing therefrom a gas phase containing undesired light hydrocarbon, passing said gas phase through said gas-liquid contact zone in countercurrent contact with only said liquid fractions passing through said gas-liquid contact zone, removing said gas phase from said gas-liquid contact zone, passing the entire amount of said gas phase removed from said gas-liquid contact zone directly to said first compression zone, and recovering a stabilized liquid fraction from said heating zone.

2. A process for the separation and recovery of a stabilized liquid fraction from a wet hydrocarbon gas mixture comprising passing a feed stream of said gas to a first compression zone and to a first cooling zone, compressing and cooling said gas in said compression zone and said cooling zone to a pressure and temperature to condense from said gas a cold liquid hydrocarbon fraction, passing said gas and said cold liquid fraction to a first separation zone, separating uncondensed gas from said cold liquid fraction in said separation zone, removing cold liquid fraction from said first separation zone, passing directly to a gas-liquid contact zone, said cold liquid fraction at a temperature not substantially higher than its temperature in said first separation zone, removing uncondensed gas from said first separation zone, passing said gas from said first separation zone to a second compression zone and to a second cooling zone, compressing and cooling said gas in said second compression zone and said second cooling zone to a pressure and temperature to condense from said gas a cold liquid hydrocarbon fraction, passing said gas and said cold liquid fraction to a second separation zone, separating uncondensed gas from said liquid fraction in said second separation zone, removing uncondensed gas from said second separation zone, contacting said uncondensed gas with a desiccant to remove water therefrom, passing said gas after removal of water therefrom to a third cooling zone, cooling said gas in said third cooling zone to a temperature to condense from said gas a cold liquid hydrocarbon fraction, passing said gas and said cold liquid fraction to a third separation zone, separating uncondensed gas from said liquid fraction in said third separation zone, removing uncondensed gas from said third separation zone, removing said cold liquid fractions from said second and said third separation zones, passing said liquid fractions from said second and said third separation zones

to a pressure reduction zone, reducing the pressure on said liquid fractions in said pressure reduction zone to separate a gas phase therefrom, removing said gas phase from said pressure reduction zone, admixing said gas phase removed from said pressure reduction zone directly with said gas entering said second compression and cooling zones, removing said cold liquid fractions from said pressure reduction zone, passing said cold liquid fractions to said gas-liquid contact zone, passing all of said liquid fractions through said gas-liquid contact zone to a heating zone, heating said cold liquid fractions in said heating zone to stabilize said liquid fractions by vaporizing therefrom a gas phase containing undesired light hydrocarbon, passing said gas phase through said gas-liquid contact zone in countercurrent contact with only said liquid fractions passing through said gas-liquid contact zone, removing said gas phase from said gas-liquid contact zone, passing the entire amount of said gas phase removed from said gas-liquid contact zone directly to said first compression zone, and recovering a stabilized liquid fraction from said heating zone.

3. A process for the separation and recovery of a stabilized liquid fraction from a wet hydrocarbon gas mixture having a low pressure comprising passing a feed stream of said gas to a first compression zone and to a first cooling zone, compressing and cooling said gas in said compression zone and said cooling zone to a pressure of about 85 pounds per square inch gage and a temperature of about 95 degrees F. to condense from said gas a liquid hydrocarbon fraction, passing said gas and said liquid fraction to a first separation zone, separating uncondensed gas from said liquid fraction in said first separation zone, removing liquid fraction from said first separation zone, passing directly to a gas-liquid contact zone said liquid fraction at a temperature not substantially higher than its temperature in said first separation zone, removing uncondensed gas from said first separation zone, passing said gas from said first separation zone to a second compression zone and to a second cooling zone, compressing and cooling said gas in said second compression zone and said second cooling zone to a pressure of about 265 pounds per square inch gage and a temperature of about 95 degrees F. to condense from said gas a liquid hydrocarbon fraction, passing said gas and said liquid fraction to a second separation zone, separating uncondensed gas from said liquid fraction in said second separation zone, removing uncondensed gas from said second separation zone, removing said liquid fraction from said second separation zone, passing said liquid fraction from said second separation zone to a pressure reduction zone, reducing the pressure on said liquid fraction in said pressure reduction zone to between about 40 and 50 pounds per square inch gage to separate a gas phase therefrom, removing said gas phase from said pressure reduction zone, admixing said gas phase removed from said pressure reduction zone with said gas entering said second compression and cooling zones, removing said liquid fraction from said pressure reduction zone, passing said liquid fraction to said gas-liquid contact zone, passing said liquid fractions through said gas-liquid contact zone to a heating zone, heating said liquid fractions in said heating zone to a temperature of about 75 degrees F. at a pressure of about 26 pounds per square inch gage to stabilize said

liquid fractions by vaporizing therefrom a gas phase containing undesired light hydrocarbon, passing said gas phase through said gas-liquid contact zone in countercurrent contact with only said liquid fractions passing through said gas-liquid contact zone, removing said gas phase from said gas-liquid contact zone, passing the entire amount of said gas phase removed from said gas-liquid contact zone directly to said first compression zone, and removing a stabilized liquid fraction from said heating zone.

4. A process for the separation and recovery of a stabilized liquid fraction from a wet hydrocarbon gas mixture having a low pressure comprising passing a feed stream of said gas to a first compression zone and to a first cooling zone, compressing and cooling said gas in said compression zone and said cooling zone to a pressure of about 35 pounds per square inch gage and a temperature of about 95 degrees F. to condense from said gas a liquid hydrocarbon fraction, passing said gas and said liquid fraction to a first separation zone, separating uncondensed gas from said liquid fraction in said separation zone, removing liquid fraction from said first separation zone, passing directly to a gas-liquid contact zone said liquid fraction at a temperature not substantially higher than its temperature in said first separation zone, removing uncondensed gas from said first separation zone, passing said gas from said first separation zone to a second compression zone and to a second cooling zone, compressing and cooling said gas in said second compression zone and said second cooling zone to a pressure of about 265 pounds per square inch gage and a temperature of about 95 degrees F. to condense from said gas a liquid hydrocarbon fraction, passing said gas and said liquid fraction to a second separation zone, separating uncondensed gas from said liquid fraction in said second separation zone, removing uncondensed gas from said second separation zone, contacting said uncondensed gas with a desiccant to remove water therefrom, passing said gas after removal of water therefrom to a third cooling zone, cooling said gas in said third cooling zone to a temperature of about 0 degrees F. to condense from said gas a liquid hydrocarbon fraction, passing said gas and said liquid fraction to a third separation zone,
